1,985,802

TRANSFERRING APPARATUS

**Joel F. Sheppard, Dover, N. H., assignor to
U. P. M. Kidder Press Co. Inc., Dover, N. H., a
corporation of Delaware**

Application December 13, 1932, Serial No. 647,002

3 Claims. (Cl. 242—55)

This invention relates to a functionally and structurally improved transferring apparatus capable of use in numerous different associations, but primarily intended for use in connection with 5 web materials which are to be transferred from one roll to a second roll, and during such transfer are adapted to be slitted and/or imprinted. The invention also contemplates the teaching of a method of transfer susceptible to being performed by such apparatus.

It is an object of the invention to provide an apparatus of this nature in which, for example, a delivery roll is placed in association with the machine and the material is slitted and distributed 10 to one or more receiving spools or shafts:

By means of the present invention it will be found that the coils of received material are distributed in such manner that they are readily capable of separation from each other without 15 danger of mutilation, and that, moreover, where desired, the web strips comprising the separate material ribs are of uniform width.

A further object is that of providing an apparatus of this nature which will embody relatively 20 few parts, each individually simple and rugged in construction, and capable of assemblage to furnish a machine operating over long periods of time with minimum of manual attention and freedom from difficulties.

Referring to the annexed drawings, there has been illustrated two practical embodiments of the invention, and in these drawings—

Figure 1 is a side view of one form of the machine;

Figure 2 is an end view thereof, and
Figure 3 shows a slightly different form of apparatus.

While the present machine is primarily intended for use in connection with the slitting and transfer of material webs, such as paper, transparent cellulose, cloth, etc., it will be appreciated by those skilled in the art that the teachings of the invention might readily be embodied in a transferring and printing machine.

Thus, it will be seen that the reference numeral 5 indicates a base which, as shown in Figure 1, rigidly mounts a standard 6. The latter supports a roll 7 which cooperates, as shown in Figure 2, either with scoring cutters 8, or else is in the form 10 of disks 9 for cooperation with shearing cutters 10. The standards 6 may also support guide rolls 11, 12 and 12', and if a plurality of receiving rolls are employed, additional guide rolls 13 and 14 may also be mounted by the standards. The base 50 55 mounts or provides track portions 15 and 16, to

each side of the standards 6. Mounted upon the former is a carriage 17 supporting a mill roll shaft 18. It is, of course, obvious that this carriage might have any desired height with respect to an adjacent supporting surface so that a minimum effort will be required to bring the mill roll to position thereon.

Mounted upon the track portion 16 is a second carriage 19. In the embodiment under consideration, two receiving rolls 20 and 21 are mounted by this carriage, and synchronous movement of these rolls is assured by, for example, a gear train 22. It is obvious, however, that if desired, the carriage 19 might merely mount a single receiving roll, in which case the apparatus could be 15 simplified accordingly. In any case it is preferred that the web or strips of material fed through the machine be moved incident to the fact that they are secured to one or more receiving rolls which may in turn be power driven by a 20 motor 23.

Referring to Figure 3, it will be noted that the base 5 provides or mounts a standard 25 which is fixed. This standard mounts one or more receiving rolls, as heretofore described. However, in this form of the invention, the central portion of the base mounts or provides track portions 26 upon which is movably mounted a carriage 27 carrying parts corresponding to those which are mounted by the standard 6 in Figures 1 30 and 2. In addition, one end of the base mounts or provides track portions 28 upon which there is movably mounted a carriage 24 which supports the mill roll shaft 18, as heretofore described.

Referring again to the first figures, it will be understood that a mill roll is positioned upon the carriage 17 and that the web is threaded around the guide roller 11, then over and around the roll 7, and thereupon under and around the roll 12. If a single receiving roll is employed, the web merely passes over and around the roll 12' and thence to the roll 21. If, however, a second receiving roll is utilized, certain portions of the web will be disposed in the manner aforesigned, but others of the same will pass only partially 40 around the roll 12' and will then transfer to the roll 13 and over and around the roll 14 and the roll 20.

If a set-up of apparatus such as has been illustrated in Figure 3 is utilized, the parts are 50 threaded in precisely the same manner as heretofore noted, it being observed, however, that while, as shown in Figures 1 and 2, the carriages 17 and 19 are shifted or permitted to move toward the standard 6, in the structure illustrated in Fig- 55

ure 3, the carriages 24 and 27 may shift with respect to the standard 25. In both instances the cutters or other apparatus supported by the standard 6 or carriage 27 are properly set up and the machine is now ready for operation.

In both forms of the invention it will be observed that the web or material strips are supported substantially constantly in their travel from the material roll to the receiving roll or rolls. In other words, there are substantially no gaps between the supporting surfaces. As a consequence of this construction, it has been found that any tendency of the web or strips to weave is virtually forestalled. In the structure shown in Figures 1 to 3, it is obvious that as the motor 23 begins to operate, the carriage 17 or 24 as the case may be—due to frictional drag—will shift to a position at which the last convolution of the material on the mill roll will be in intimate contact with the guide roll 11 and this will be true throughout the entire operation, and despite the decreasing diameter of the mill roll, as the material is unwound from the same. Also, incident to the drag of the material the carriage 19 or 27 will shift to positions at which the receiving roll will be constantly in intimate contact with the last guide roll. Of course, if the construction shown in Figures 1 and 2 is employed, the tensioning rolls 12' and 14 will be in contact respectively with rolls 21 and 20. It will be appreciated that regardless of this factor, however, as the receiving roll or rolls "build up" incident to the increasing number of material convolutions upon their bodies, the carriage 19 will be free to shift outwardly without, however, in any sense of the word affecting the fact that there will be no gaps or spaces within which the material web or strips are unsupported.

In the case of apparatus such as shown in Figure 3, the carriage 24 will shift increasingly toward the guide roller 11 as the convolutions of the mill roll decrease in number, and likewise the carriage 27 will shift increasingly away from the receiving rolls 20 and 21 as the diameters of these rolls increase.

Thus, among others, the several objects of the

invention as specifically aforesaid, are achieved. It will be appreciated that numerous changes in construction of the apparatus and variations in the steps of the method might be resorted to without departing from the spirit of the invention as defined by the claims.

Having described my invention, what I claim as new and desire to secure by Letters Patent is:

1. A transfer apparatus including means for operating upon material, a delivery roll, a receiving roll, means for fixedly supporting such receiving roll against other than rotating movement, material operating means and means for supporting said operating means to reciprocate with respect to said receiving roll, whereby to substantially constantly support the material in its movement from one roll to the other.

2. A transferring apparatus including a base, track portions associated with said base and extending substantially horizontally, carriages mounted upon said track portions, a delivery roll mounted by one of said carriages, material manipulating rolls mounted by the other of said carriages, a support fixed with respect to said base, a receiving roll carried by said support and a motor coupled to said receiving roll, whereby a web of material extending from said delivery roll through said operating rolls to said receiving roll will draw said carriages towards each other and towards said receiving roll to maintain said rolls in peripheral contact with the material substantially constantly supported by said several rolls.

3. A transferring apparatus including a base, track portions forming a part of said base, carriages mounted upon said track portions, material manipulating rolls upon one of said carriages, a support fixed with respect to said base, a receiving roll and a delivery roll, one of said rolls being disposed upon the second of said carriages and the other of the same being mounted by said fixed support, whereby upon said receiving roll being driven, said carriages will be drawn towards each other and towards the fixed support.

JOEL F. SHEPPARD.
